a corporation of New Jersey

Application December 28, 1948, Serial No. 67,684

38 Claims. (Cl. 100—4)

1

This invention relates to apparatus for bundling elongated articles with wire or the like, and more particularly to a machine for wrapping and fastening wire around a plurality of lengths of pipe at a number of spaced localities, to provide a securely tied bundle for shipment, storage or other handling.

Although some apparatus for this purpose has been proposed heretofore, it has remained a common practice in plants that manufacture pipe, to bundle the product by hand, e. g. by first assembling a number of lengths side-by-side and then manually wrapping and tying the assembly with wire at several places along it. Especially for the smaller sizes of pipe, from less than one inch up to three inches or so outside diameter, the bundling operation is a practical necessity not only to facilitate loading, unloading and the like, but also to avoid damage by bending, when the pipe is in transit; yet the manual wrapping and tying steps are slow, inefficient, and apt to be non-uniform in result.

Accordingly an important object of the invention is to provide new and improved apparatus for bundling an assembly of pipe lengths or similar articles with wire, and especially to effectuate such operations in a wholly automatic and yet very secure manner. Further objects are to provide more reliable mechanism, positive in action, for wrapping wire about a bundle of pipe, and to provide an improved device which grasps the wire and positively draws it around the bundle. A more specific object is the provision of structure whereby the end of a wire is engaged and carried around the group of pipe lengths and fastened to a standing portion of the wire, all while the relative positions of the pipe and wire are adjusted to avoid premature binding action by the wire and to assure a tight wrapping all around.

Additional objects are to provide an automatic machine for bundling pipe, having improved and more durable means for passing wire around the pipe, having novel and peculiarly effective structure for twisting the ends of each wire wrapping together to fasten the same, having efficient and positive-acting structure for separating the wrapped and fastened wire from the supply wire, and having new and advantageous means and combinations for actuation and automatic control of the several operating instrumentalities.

A further object is to provide a pipe-bundling machine of the character described, including means adjustable to accommodate pipe of a variety of lengths, and also preferably including

5 means for wrapping and fastening wire around the bundle at any of various selectable localities along the length of pipe. A related object is the provision of apparatus of the nature stated involving a plurality of wrapping devices mounted and related for wrapping the bundle with wire at a corresponding plurality of places along its length, such apparatus further including efficient means for actuating and controlling the wrapping devices in appropriate synchronism.

10 A particularly important object is to provide a novel pipe-bundling apparatus, wherein the pipe is advantageously introduced lengthwise and is similarly removed, such apparatus preferably including advantageous and reliable structure for so advancing an assembly of pipe into wrapping position, for arresting the pipe and for similarly advancing the bundle lengthwise from the machine upon completion of the 15 wrapping operation.

20 To these and other ends a specific embodiment of the apparatus is described below and shown in the accompanying drawings, by way of example, such description and drawings being believed to disclose, in an illustrative manner, the 25 novel features, combinations and principles of the invention.

Referring to the drawings:

Fig. 1 is a plan view of a pipe-bundling machine representing one advantageous embodiment of the invention;

Fig. 2 is a side elevation of the machine of Fig. 1, the illustrations of Figs. 1 and 2 being abbreviated for clarity as indicated by the broken lines;

Fig. 3 is an enlarged vertical section on line 3—3 of Fig. 2, showing one of the wrapping mechanisms in elevation at the pipe-entering side, certain parts being broken away for clarity;

Fig. 4 is an enlarged vertical section on line 4—4 of Fig. 2, showing the same wrapping mechanism in elevation at the forward or pipe-leaving side, certain parts being broken away for clarity;

Fig. 5 is a detail section, further enlarged, on line 5—5 of Fig. 4;

Fig. 6 is a further enlarged section on line 6—6 of Fig. 3;

Fig. 7 is a still further enlarged, detail section on line 7—7 of Fig. 6;

Fig. 7A is a greatly enlarged perspective view showing a wire-guiding bar of Fig. 7, and an associated part, in disassembled relation;

Fig. 8 is a fragmentary detail view, in elevation, of a stop device and other parts at the pipe-entering side of the mechanism of Fig. 3;

Fig. 9 is a section on line 9—9 of Fig. 8;

Fig. 10 is a fragmentary, enlarged, horizontal section, abbreviated in length, showing certain structure at the lower part of the mechanism at Fig. 3, taken generally on line 10—10 of Fig. 3;

Fig. 11 is a vertical section on line 11—11 of Fig. 10;

Fig. 12 is a fragmentary, detail elevation, partly in section, showing certain wire gripping and other parts at the forward side of the mechanism of Fig. 4;

Fig. 13 is an enlarged section on line 13—13 of Fig. 12;

Fig. 13-A is a fragmentary section on line 13A—13A of Fig. 13;

Fig. 14 is an enlarged section on line 14—14 of Fig. 12;

Fig. 15 is a fragmentary plan view, somewhat enlarged, of certain wire-engaging structure shown in Fig. 7, some parts being broken away for clarity and this figure being essentially a section on line 15—15 of Fig. 16 hereinbelow described;

Fig. 16 is essentially a side elevation of the structure shown in Fig. 15;

Fig. 17 is essentially an end elevation of the structure of Figs. 15 and 16;

Fig. 18 is a detail elevational view, enlarged, and partly in vertical section, of certain wire guiding parts shown in Fig. 4;

Fig. 19 is a section on line 19—19 of Fig. 18;

Fig. 20 is a detail section on line 20—20, enlarged, of Fig. 4;

Figs. 21, 22, 23, 24 and 25 are simplified, diagrammatic views generally corresponding to Fig. 4 and respectively showing successive positions of certain parts at corresponding stages of operation of the wrapping mechanism;

Fig. 26 is a simplified, diagrammatic, perspective view of certain operating parts of the machine; and

Fig. 27 is a timing diagram illustrating the timing relationship of various control and operating instrumentalities.

The apparatus illustrated in the drawings is designed to receive a group of lengths of pipe, assembled in a bundle-like, side-by-side relation, and to wrap and fasten wire around the assembly at a plurality of spaced localities along it. The assembly of pipe is fed endwise into the machine, where it is arrested for the wrapping operation. When the bundling, which takes place simultaneously at all of the selected localities, is completed, the bundle of pipe is then advanced endwise from the machine, i. e. along the same line of travel parallel to the axes of the pipes.

Referring first to Figs. 1, 2, 3 and 4, the complete machine comprises an elongated supporting structure or bed plate generally designated 30 and including a laterally spaced pair of supporting rails or beams 31, 32 which extend, in parallel relation, for the entire length of the machine. Carried on these rails are a plurality of identical wrapping mechanisms generally designated 40, 40a and 40b and disposed at selectable, spaced localities along the apparatus. The supporting structure also includes a long rack 42 which extends the entire length of the machine. Each of the wrapping mechanisms 40, 40a and 40b carries a horizontal shaft 43, journaled for rotation and having mounted thereon a pinion 45 which meshes with the rack 42. Each of the shafts 43 has a projecting, squared end 46 which may be engaged by an appropriate tool to turn

the shaft. Since each of the wrapping mechanisms 40, 40a 40b is free to slide, against friction, on the supporting rails 31, 32, the position of each mechanism in the lengthwise direction of the machine can be adjusted within a wide range by manually turning the corresponding pinion 45 at the shaft end 46. In consequence the apparatus may be adjusted to accommodate pipes of various lengths, i. e. to handle assemblies of long lengths, or of intermediate, or of short lengths, and the specific localities at which wrappings of wire are to be placed for a given value of pipe length may likewise be chosen within a relatively considerable range. It may be explained that although the illustrated machine includes three wrapping mechanisms 40, 40a, 40b to provide a fastened turn of wire at each of three corresponding places along the length of pipe, greater or fewer numbers of these mechanisms may be employed, the broken away portion of Figs. 1 and 2 further indicating that the machine may be conveniently longer than actually shown, and may for instance include an additional wrapping mechanism, identical with those illustrated, intermediate the devices 40 and 40b.

For support of an assembly of pipe entering or leaving the machine, a plurality of peripherally grooved or concave idler rollers 48, 49 are provided, carried on the base structure 30 and conveniently disposed intermediate successive wrapping units. Each idler roller is journaled for free rotation about a horizontal axis. Each of the wrapping mechanisms 40, 40a and 40b is provided with a similar grooved or concave roller 50 mounted on a shaft 51 (Fig. 3) which is journaled for rotation on a horizontal axis, by suitable bearings 52, 53. The shaft 51 extends to an electric motor drive unit generally designated 55 which may be of any suitable construction and include appropriate reducing gears, not shown in detail, to turn the roller 50 at a desired speed. The rollers 48 and 49 and the several rollers 50 are all aligned in a direction lengthwise of the machine so that their uppermost grooved surfaces lie in a single straight line and conjointly provide a supported pathway of movable members, for pipe traversing the apparatus. That is to say a group or assembly of pipes to be bundled may be fed, for instance, onto the rollers 50, 49 and so on from the right-hand end of the machine as seen in Fig. 1, the assembly being then advanced along and by the successive rollers 50 until it lies wholly within the machine or is otherwise centered therein in the desired position for wrapping operation. Upon the completion of wrapping operation the bundle of pipe is then similarly advanced by and upon the driven and idler rollers, so as to travel from the machine in an endwise direction, leaving it at the left-hand end of Fig. 1. It will be understood that appropriate feeding and receiving tables or the like (not shown) may be disposed adjacent the right and left-hand ends of the machine as shown in Figs. 1 and 2, so that by manual or mechanical means successive groups of pipe may be assembled and inserted lengthwise into the machine, and so that the finished bundles ejected in a similar fashion may be removed for shipment, storage or other disposition. It will be understood that the idler rollers 48, 49, if desired, may be so mounted on the rails 31, 32 as to be slidable lengthwise of the machine, for corresponding adjustment of the position of each to afford the most advantageous pipe-supporting arrangement for any selected length of pipe.

For actuation of the wrapping instrumentalities in the several mechanisms 40, 40a and 40b, a main drive shaft 58 extends substantially the entire length of the machine, through each of the wrapping mechanisms. Directly associated with and mounted on the shaft 58, a magnetic clutch 60 is provided, having a driving sprocket 62 concentric with but rotatable relative to the shaft 58. The magnetic clutch 60 is of a suitable, known type having one element keyed to the shaft 58 and its coacting element connected to the sprocket 62, the details of the clutch structure being omitted for clarity of illustration. A main source of driving power, conveniently comprising an electric motor drive unit 64 is mounted alongside of the supporting structure 80, the drive unit being of a suitable, known type, including appropriate reduction gearing (not shown in detail) to afford drive of the shaft 58 at a desired speed, such drive being effectuated by a sprocket 65 turned by the motor unit 64 and a chain 66 engaging and coupling the sprockets 62 and 65.

For certain control and timing purposes explained in more detail hereinbelow, the main shaft 58 has mounted on it a sprocket 68, which thus turns with the shaft, and which through transmission mechanism comprising a chain 69, a second sprocket 70, coupled by the chain to the sprocket 68 and carried on a countershaft 71, a gear 72 on the countershaft and a gear 73 meshing therewith, drives a timing drum shaft 75 upon which the gear 73 is carried, these parts being also shown in Fig. 26. It will be seen that when the magnetic clutch 60 is engaged, the motor unit 64, which may turn continuously if desired, drives the shaft 58 and instrumentalities operated thereby, including the shaft 75 just mentioned.

Since each of the wrapping mechanisms such as 40, 40a and 40b is conveniently identical with the others, description of a selected one of such mechanisms, e. g. the device 40, will be understood to be sufficient. Referring therefore more particularly to Figs. 3 and 4, and also other figures such as Figs. 6 and 10 for certain details, the mechanism 40 includes an upright supporting plate 80 carried on a horizontal plate 81 which provides the base for the mechanism resting on the rails 31, 32 as hereinabove described. The upright plate 80 has a large opening 82 of generally circular configuration, at its central part and in alignment with the upper surfaces of the driven and idler rolls 48, 49, 50, so that successive assemblies of pipe may pass through the mechanism. Three grooved or concave rollers 84, 85 and 86 are disposed around this opening 82, on the pipe-leaving or forward face of the plate 80, as shown in Fig. 4, the rollers being substantially equally spaced in a circumferential direction around the opening. Each of the rollers is mounted for rotation on a horizontal axis, and they all engage the circular periphery of a large ring member 88. It will be noted that the rollers have a truncated V-shaped groove and the periphery of the ring 88 has corresponding beveled faces 89, 90, whereby the three rollers conjointly support the ring so that the latter may turn about a horizontal axis parallel to the axes of pipe and their direction of travel through the machine. The central aperture of the ring 88 corresponds generally to the central aperture 82, likewise for passage of the assembly of pipe therethrough. The central portion of the ring periphery has gear teeth 91 which mesh with

corresponding teeth 92 around the bottom of the groove of roller 84, the bottoms of the grooves on the other rollers 85 and 86 being shaped to clear the teeth 91, as illustrated in the case of the roller 86 in Fig. 10. The roller 84 is attached to an adjacent coaxial sleeve 94 journaled in the adjoining portion of the supporting plate 80, the roller 84 and its sleeve being likewise disposed coaxially with the main drive shaft 58, which traverses both the roller and sleeve. The main drive shaft 58 carries a key 96 which engages a corresponding keyway or groove on the inside of the opening of the roller, whereby rotation of the shaft 58 correspondingly effects rotation of the roller. It will be appreciated that the key 96 on the main shaft may extend a considerable distance along the latter in the vicinity of each of the driving mechanisms 40, 40a and 40b and that the roller 40 is free to slide lengthwise along the shaft (the associated sleeve 94 appropriately clearing the shaft and key) so that the roller 84 will be coupled to the shaft at the various positions of adjustment of the corresponding wrapping mechanism lengthwise of the machine. It will also now be seen that as the shaft 58 turns, the ring 88 is rotated in its support by the three rollers 84, 85 and 86, by virtue of the geared coupling through the roller 84.

The uppermost roller 85, is mounted, for free rotation, by means of a pin or stub shaft 98 suitably journaled in the plate 80, and the lower roller 86 is similarly mounted for free rotation, on a pin 99. Although a simple bearing may be employed for the pin 99 if desired, the illustrated device includes spring tension means for mounting this lower roller 86, in order to take up wear which may develop during the life of the apparatus and also to compensate for possible errors in machining of the described instrumentalities. Thus the shaft 99 is eccentrically disposed in a sleeve 100 which is journaled in the plate 80 and which carries at its opposite end an arm 101. The outer or lower end of the arm 101 is connected to one end of a compression spring 103 which is disposed around a threaded rod 104, the other end of the spring 103 being secured to the rod by a nut 105. The rod is fixedly mounted at 106 to appropriate supporting structure 107 carried by the base plate 81. The spring 103 being under compression, the arrangement of the arm and eccentrically apertured sleeve 100 resiliently forces the roller 86 against the tapered edges 89, 90 of the ring and thus keeps the ring firmly seated in the three rollers.

Referring now also to Figs. 12 and 13, the ring 88 carries a wire gripper generally designated 110 which is adapted to engage the end of a wire (received from a supply as described hereinbelow) so that upon rotation of the ring the end of the wire is carried around an assembly of pipe 112 which may be disposed in the machine. The wire gripper comprises a pair of jaw bodies 113, 114 shaped to constitute complementary halves of a frusto-conical shape as will be apparent from the illustration of the body 113 in Fig. 13. The bodies 113, 114 thus have adjacent plane faces as shown at 113a in Fig. 13 and their outer frusto-conical surface is received in a roller bearing 115 mounted in the ring 88. The rear part of each body is a projecting portion 116 having a peripheral configuration constituting a half of a spherical zone, the curved surface provided by the complementary halves of the two bodies being received in a further roller bearing 117 also carried by the ring 88, coaxially with the first bearing 115. It will be

seen that upon displacement of the jaw bodies 113, 114 to the left as seen in Fig. 13 by means described hereinbelow, the jaw bodies may separate and may also rock slightly in a vertical or other transverse direction, by virtue of the curved surface of the portions 116. A hardened steel block or insert 119 is mounted in a recessed region between bodies 113, 114 (Figs. 13 and 13A), being secured to one of them, e. g. body 113, by a single screw 120. The insert 119 serves as a shear blade in cooperation with a movable shear blade hereinbelow described, for severing the wires adjacent the gripper at the desired time. More specifically, the shearing surface or knife is constituted by whichever of the forward portions of the plane edge surfaces 119a, 119b of the insert is lowermost, depending on the gripper position, which reverses on each cycle of operation. When these forward surfaces are worn, the insert can be loosened and turned to substitute the edge portion originally at the rear. The single screw fastening 120 facilitates such operation and also ultimate replacement of the insert.

The jaw bodies 113, 114 also carry recessed projecting portions 121, 122, the facing recesses of the latter being arranged to support cooperating jaw elements 123, 124. These gripper jaws 123, 124 are respectively supported or retained, with a loose fit, on screws or studs 125, 126, so that each of them may swing laterally, i. e. about the axes of the studs 125, 126. The recesses of the jaw body portions 121, 122 are shaped only slightly larger than the width of the jaws 123, 124, e. g. as shown in Figs. 12 and 13, so that this permissible swinging motion of the jaws is about 3° in each direction from the central position shown. A pair of coil springs 129, 129 are disposed under compression between the jaw bodies 113, 114, the springs 129 being advantageously seated in recesses in the opposing faces of one body 114 and of the insert 119 that is secured to the other body 113.

To hold the jaw bodies 113, 114 together, a stud 130 is provided, having an enlarged head 131 seated in complementary recesses of the adjacent faces of the bodies. The stud 130 projects rearwardly and is urged in an outward direction by a coil spring 132 acting under compression against a nut 133 on a threaded portion of the stud 130. So long as no pressure is exerted on the outer end of the stud 130, the spring 132 keeps the jaw bodies closed and likewise the jaws 123, 124. To release the gripper at desired times, a lever 135 (Fig. 7) is pivoted to a suitable arm on a housing structure 136 which is carried at the upper part of the plate 80 and which serves other purposes as hereinbelow described. The lever 135 is also linked, at a remote point, to the retractable core 138 of a solenoid 139, the lever being normally held by a spring 140 under tension, so that the lower end 141 of the lever exerts no pressure on the outer end of the stud 130. When the solenoid 139 is electrically energized the core 138 is retracted, i. e. to the right as seen in Fig. 7, rocking the lever about its pivot and pushing the stud 130 to the left (Figs. 7 and 13) against the spring 132. As a result the jaw bodies 113 and 114 are forced somewhat outwardly of the bearings 115, 117, whereby the springs 129, 129 separate the bodies and likewise the jaws 123, 124.

As stated, the gripper jaws 123, 124, when closed, engage an end portion of the wire between them, to pull the wire around the pipe assembly while the ring 88 turns. Such operation im-

parts tension to the wire, which in turn causes the jaws to swing about the studs 125, 126, within the limited freedom for such motion explained above. As a result, the ribbed and grooved wire-engaging faces of the jaws are forced more tightly together, against the wire and to the extent that the conforming ribs or teeth, and grooves, at one side of the mating jaw faces, may actually crimp the wire. This action is enhanced by a camming or wedging effect of the ends of the recesses of the bodies 113, 114 in which the jaws fit, i. e. in that the ends of the jaws opposite their notched faces are square or flat so that any angular movement of the jaws forces them together, the wedging effect being permitted by the loose fit of the studs 125, 126. In consequence, the tension on the wire as the jaws move around with the ring causes the jaws to rock and to bite the wire with a tighter grip.

In the manner described, the gripper jaws are adapted to engage and hold the end of a wire fed from a reel or other suitable continuous source thereof (not shown) through a tensioning device shown in Figs. 4, 18 and 19. The tensioning device comprises a pair of cooperating rollers 144, 145 each having its periphery grooved as shown in Fig. 19, with a curved cross-section but to a depth less than the radius of the wire expected to be used. The roller 145 is journalled for free rotation on one arm of a bell crank lever 147 pivoted to a portion of the supporting structure and having its other arm biased by a spring 148 under tension so that the roller 145 is urged toward the roller 144 and so that the wire 150 passing between the rollers from a guiding member 151 will engage both rollers in frictional, rolling contact as illustrated in Figs. 18 and 19. The roller 144 is also mounted for rotation, on the supporting structure constituted by the plate 80, but includes a one way clutch indicated at 152 and connected between the roller and supporting structure so as to prevent rotation of the rollers except in the direction in which the wire is fed. A frictional drag is also exerted on the larger roller 144 by means of a conical spring 154 disposed between the face of the roller and the head 155 of stud 156 upon which the inner element of the one way clutch 152 is secured. The head 155 may be adjusted along the stud, to adjust correspondingly the pressure on the roller. By virtue of these instrumentalities, wire may be drawn between the rollers, but will not move backward relative to them when the tension upon it is released; nor will the rollers tend to spin and advance the wire at a faster rate than that at which it is actually being withdrawn. The wire tensioning device is conveniently disposed, as shown, at an outer and upper portion of the plate 80, outside of the ring 88 and adjacent to the starting or rest position of the gripper 110, e. g. the position occupied by the latter in Figs. 7, 12 and 21.

As will be apparent by inspection of Figs. 21 to 25 the rotation of the ring for one complete turn carries the gripper 110 completely around the circle, thus drawing the end of the wire 150 around the assembly of pipe to be bundled. During the time that the wire is being carried around the pipe and during certain further operations, the pipe assembly is preferably separated from the driven and idler rollers 50, 48 and 49. A primary means to that end comprises a vertically slideable plate 160 (Fig. 4) having a deep V-shaped recess 161 at its upper end and

arranged to reciprocate vertically relative to a transverse supporting bar 163. The supporting bar 163 also carries an air cylinder 164 having its piston rod 165 connected to the plate 160 so that when air or other fluid under pressure is admitted to the cylinder, the plate is moved upwardly to a predetermined elevation relative to the bar 163. As will be seen in Fig. 4 these parts are so disposed that in the retracted position of the air cylinder piston, the plate 160 has its upper V-shaped edge completely below any pipes that may be disposed on the rollers 48-50. As the plate moves upward it engages the assembly of pipe and lifts the same clear of the rollers, it being understood that the lifting plates 160 of the several wrapping mechanisms operate in substantial unison whereby the pipe assembly is lifted throughout its length at the same time. Although other configurations of the recess in the plate 160 may be employed, the illustrated, curved-bottom V-shape, comprising an angle of about 60° (each straight portion of the V making an angle of 30° with the vertical), has been found particularly suitable for bundling pipe, especially groups of from 3 to 10 or 15 pieces, in that this configuration causes the group of pipes to assume a relationship of optimum compactness in the wrapping operation.

At the end of the travel of the gripper around the pipe, the end portion of the wire is twisted to the remote part of the latter, which may be conveniently designated the "standing" part or portion of the wire. To twist these portions of wire together, there is provided a twisting wheel or gear generally designated 170 and disposed to turn about an axis which lies on a line extending between the pipe assembly at the center of the ring opening and the starting or rest position of the gripper 110 (see Fig. 21). This twisting gear (Figs. 6, 7 and 12) has a flat underface 171 but at its other side has a large annular recess providing a central hub portion 172 and an outer flange portion 173, the latter being externally toothed for drive of the element. The twisting gear is supported for rotation by structures separated, in the direction of pipe travel and along a plane substantially coinciding with that in which the wire 150 moves as it is drawn around the pipe by the gripper. On the pipe entering side of the mechanism, such supporting structure comprises the housing 136 having a suitable semicircular flange 174 entering the annular recess of the twisting gear, and a lower plate structure 176 which projects over the bottom face 171 of the twisting gear, the housing structure 136-176 being mounted on the plate 80, chiefly in a position on the pipe entering side but with a portion projecting through the opening of the ring 88 to provide the supporting structure 174 and the supporting part of the plate 176 as just described. At the other side of the twisting gear a similarly flanged supporting element 178 is provided for engagement with the annular recess of the gear, the element 178 being secured in a supplemental housing 179 carried on the forward face of the plate 80, as shown in Fig. 6.

The twisting gear 170 has a radial slot 181 extending from one edge conveniently just past the axis of the element, and the upper half of the hub beyond the axis is also conveniently slotted as shown in Fig. 7 to constitute a continuation of the slot 181. The entering edges of the slot 181 are appropriately beveled or curved so as to facilitate sidewise entry of the wire 150 into such

slot. As will be apparent from inspection of Figs. 21 to 25, inclusive, the relation of the twisting gear to the wire gripper and the ring is such that with the slot 181 disposed in the plane of the ring face and opening in one direction, wire may be moved into the twisting gear from such direction; and when the twisting gear is turned around so that the slot lies in the same plane but facing in the opposite direction, wire may also be received in the slot, but from the latter direction. It will also be noted that the supporting and bearing structure for the twisting gear, as described above, is completely separated along this plane whereby wire may move freely into the twisting gear from either direction (see especially Fig. 6).

For drive of the twisting wheel a train of gears comprising a pinion 184 meshing with the twisting gear and also with a larger gear 185 are provided. The shaft of the gear 185 carries a smaller gear 186 which meshes with a rack 188 mounted in suitable guides 189, 190 so that it may slide past the gear 186 to rotate the same. The gear train is appropriately housed and journaled for rotation by the structure 136-176 as shown in Figs. 6 and 7. A supporting framework 192 extends from one side of the housing 136 and the plate 80, to carry an air cylinder 193, having a long piston rod 195 aligned with and connected to the rack 188. The air cylinder 193, as in the case of other air cylinders herein described, is of double acting type, controllable by admission of fluid under pressure to one end or the other to drive the rack 188 in one corresponding direction or the other as shown in Fig. 6. Although other types of operation, e. g. to make fewer or less twists may be employed if desired, the apparatus illustrated is designed and controlled so that a full stroke of the piston rod 195 in either direction rotates the twisting gear precisely 4½ complete turns.

As will be further apparent from Figs. 21 to 25, the arrangement is such that at the completion of the circuit of the gripper 110, both the end portion and the standing portion of the wire 150 are disposed in the slot of the twisting gear, which is thereupon rotated to twist the wire together, actually both below and above the gear. In order to separate the resulting bundled pipe from the supply portion of the wire, the pair of wires in the gear are severed immediately adjacent the underface of the latter, whereby the twist adjacent the bundle remains in place, holding the two ends of the wrapped wire in fastened relation. At the same time there remains a short piece of wire which is twisted to the standing portion just above the twisting gear, and the standing or supply portion of wire is also severed, adjacent the gripper so that a fresh end of wire is constituted to be engaged by the gripper for wrapping operation on a succeeding bundle of pipe. To effectuate the severing operations, a box-like shearing head is provided, generally designated 200 and arranged to slide transversely through the housing 179 as shown in Figs. 7, 15, 16 and 17. This shearing head is pivotally connected at 201 to a lever 202 which has a short arm pivoted to a bracket 204 projecting from a supporting portion 205 of the housing structure 179, and which has a long arm 206 pivotally connected to the end of the piston rod 208 of an air cylinder 210, the latter being in turn pivotally mounted at 211 adjacent an upper edge of the plate 80. The instrumentalities last described are particularly shown in Fig. 6, it be-

ing noted from Figs. 3 and 4 that the plane of these elements and likewise of the twisting gear, and its drive train and rack, lies at an angle of about 45° to the horizontal, i. e. so as to dispose the several parts in the intended relation to the gripper when the same is in its starting or rest position.

The shearing head 200 carries upper and lower shearing blades 214 and 215, mounted in the head and disposed to project toward the face of the ring 88 and specifically toward a line extending from the rest position of the gripper, through the axis of the twisting gear to the bundle of pipe that is subjected to the wrapping operation. The lower blade or knife 215 is disposed to slide across the underface of the twisting gear, while the upper blade 214 is disposed to slide to and beneath the underface of the hardened gripper jaw insert 119 as described above and as also shown in Figs. 13 and 16. It will now be seen that upon actuation of the air cylinder 210 to retract the rod 208, and thus move the lever 202—206 counter-clockwise about its end pivot (as seen in Fig. 6), the shearing head and its blades 214, 215 are moved inwardly across the path of the wire, severing the wire or wires at the described localities.

In order to align or hold the wire or wires intermediate the gripper and twisting gear, and also to facilitate entry of successive portions of wire into the gripper, further mechanism is preferably included, as shown particularly in Figs. 7, 15, 16 and 17. A finger 220 is slidably mounted within the box-like structure 200 that constitutes the shearing head, the finger 220 being adapted to project just into the path of wire intermediate the twisting gear and the rest position of the gripper. Bearing in mind that the direction of rotation of the ring 88 is such (i. e. counter-clockwise as seen in Fig. 4) as to carry the gripper first along a path where it moves in a direction which is upward in the view of Fig. 15, the finger 220 has a flat side 221 facing in the direction in which the wire is returned to the axis line of the twisting gear, at the completion of ring travel, and a curved or tapered side 222 facing the direction in which the wire first comes to the twisting gear at an intermediate stage of ring travel, i. e. as in Fig. 23. A supplemental wire control bar 224 is disposed alongside the finger 220, and is likewise slidable through the shearing head 200. The outer end of the wire control bar 224 is slightly spaced from the flat face 221 of the finger 220, i. e. so as to provide a slot or groove 226 between these elements. The bar 224 also carries a projection 227 which engages a similar, complementary projection 228 on the finger 220, so that in the position of Fig. 15 the projection 227 from the bar 224 prevents further outward movement of the finger 220 which might otherwise occur under the force of a compression spring 230 that backs up the finger. The sliding bar 224 is coupled to an operating bar 232 in turn pivotally connected to the piston rod 234 of an air cylinder 235 (Figs. 6 and 7), whereby upon drive of the piston rod 234 in and out, the wire control bar 224 is reciprocated into and out of the wire path between the gripper and the twisting gear.

Thus with the parts in the position of Fig. 15, the finger 220 simply serves as a stop for the wire in the direction in which the gripper first travels, i. e. so that as the standing portion of the wire is carried toward the twisting gear, as shown in Fig. 23, and is then brought to the center or axis line of the twisting gear by oper-

ation as hereinafter described, such wire portion slides over the curved surface 222 of the finger and is then held (after having been carried slightly inward by a first half turn of the twisting gear, thus clearing the end of the finger) by the flat face 221 of such finger. The finger also serves to back up the described wire portion when the end portion of wire is again brought to the axis line of the twisting gear and is disposed against the standing part of the wire as actually shown in Fig. 15, the standing portion of the wire being designated 150a and the returned end portion being designated 150b. Assuming now that the air cylinder 235 is operated to drive the bar 232 to the right as seen in Figs. 7, 15 and 16, the wire control finger 224 is brought up to the pair of wires, engaging them in the slot between the finger and bar. At the same time the advance of the projection 227 permits the finger 220 to move outwardly along with the wire control bar (under the pressure of the spring 230), thereby further backing up the wires and cooperating in the described positioning action.

As the cycle of wire travel is completed, it is desired to locate the standing portion 150a of the wire in the jaws of the gripper; and to cooperate in forcing the wire past the tapered or flaring, entering the edges of the gripper jaws, a pusher bar 240 is provided having a T-shaped configuration as shown at 241 in Figs. 16 and 17 and disposed to reciprocate through appropriate supporting structure 242 above the housing 179. At its rear end, the pusher bar is mounted on a bracket 244 which is secured to the upper side of the driving bar 232. In consequence the pusher bar 240 is reciprocated with the wire control bar 224, moving out to push the wire into the gripper jaws at the same time that the control bar and the finger 220 move outwardly to straddle the pair of wires and hold them during the twisting operation.

It may be explained that while the gear 170 is actually effectuating a twist of the wire both below and above it, the gripper jaws are open, the finger 220 and bar 224 serving (as just explained) to hold the wires during such operation. Since the twist in the wires above the twisting gear effectively shortens them in the distance between the finger 220 and the gear, the control bar and finger are so arranged and mounted that they may rock or tilt downwardly at such time. Thus the control bar 224 is connected to the driving bar 232 by a hinge or pivot 246 having a horizontal axis, and a lower inside face 248 of the box-like structure 200 is sloped downwardly as shown in Figs. 7 and 16, to permit the described motion. The finger 220 is mounted in a movable guide element 249 which is likewise free to move downwardly so that the finger can also be carried down with the control bar 224, as when the twist shortens the wires. As the bar 224 and finger 220 originally move out to engage the wires, the latter are backed up by a plate 250 (see also Figs. 12 and 13) that overlies an arcuate region at the lower edge of the gripper assembly. The plate 250 has a curved configuration as seen in Fig. 12, in order to permit the gripper to turn in its bearings, and in the specific device shown the backing plate cooperates in holding the bearings in place. It will be noted that but for the plate 250 the wires 150a, 150b might tend to spring away from the control bar and finger.

As will be apparent from Figs. 23 and 24 the path of the standing part of the wire, during the

actual wrapping, brings it into the slot of the twisting gear 170, and as elsewhere explained herein the twisting gear is preliminarily rotated so as to present its slot in the opposite direction at the completion of the cycle of gripper motion, the slot having already received the standing part of the wire before such preliminary rotation. In order to insure disposition of the wire well within the slot, and indeed at the center of the twisting wheel, there is provided a centering bar 252 (Figs. 6, 7 and 15), which lies immediately beneath the twisting gear at the side adjacent the ring 88 and which has a wire-guiding edge 254 comprising two concavely curved portions meeting at a central, rounded apex as shown. This centering bar 252 has projecting means 254a (see Fig. 7A), which may be pin-like but is conveniently shown as a rib-like structure extending beneath the bar 252 and between its ends 255, 256, and which travels in a groove 257 that is somewhat longer than the bar 252 and that is formed in the recess 261a (of the member 261, that is part of the plate structure generally designated 116) which admits the bar 252, it being recalled that the plate structure 116 underlies the surface 171 of the twisting gear to cooperate in retaining the latter in place. The bar 252 is thus adapted to slide along the groove 257, i. e. in the direction toward the top or bottom of the view of Fig. 15, or toward and away from the observer in Fig. 7, and is frictionally retained against casual displacement by a spring pressed ball 259. It will now be understood that when the wire enters the slot of the twisting gear, e. g. as in Fig. 23, it may not penetrate to the inner end of the slot. However, when the twisting gear turns it brings the wire against one of the curved sides of the edge 254 of the bar and the latter consequently forces the wire toward the center of the gear. At the same time the centering bar 252 is moved, by the pressure of the wire, to the other end of the groove 257, where it is in place to perform a similar centering function when a wire enters the twisting gear slot from the other direction. As shown in Fig. 6 the bar 252 is in position to operate for centering the end portion 150b of the wire when it is brought into the slot as indicated in Fig. 25. In Fig. 15 the bar 252 is shown, for purposes of illustration, at its opposite position, ready to operate on the next introduction of a standing part of the wire (Fig. 23); it will be understood that the particular relation of the twisting gear slot and the bar 252 set forth in Fig. 15 only exists at one of the instants during the twist-making rotation of the gear 170, i. e. as the gear completes a first, second or like complete turn prior to its arrest in a position with the slot facing the other way.

The apparatus also preferably includes additional means for insuring complete centering of the wires 150a, 150b when the twisting operation is to commence. Referring to Figs. 4, 5 and 12 a pusher plate 260, guided by a pin 262 which traverses a slot 263 in the plate, is disposed so that its V-shaped notch 264 faces the axis of the twisting gear at a locality just below the latter and in a direction along the pipe-leaving face of the ring 88. More specifically, the pusher plate 260 is arranged at the side of the twisting gear to which the end portion of the wire is returned as shown in Fig. 25, the pusher being adapted to reciprocate toward and away from the twisting gear axis so as to push the wire 150b (see also Fig. 15 which likewise shows the plate 260) and with it the wire 150a, squarely to the center of the

twisting gear. The pusher plate 260 is pivotally connected to the piston rod 266 of an air cylinder 267 which is adapted to provide the desired reciprocating drive for the pusher plate at appropriate times, it being understood that the cylinder 267 and the guide pin 262 are carried by suitable portions of the fixed, supporting structure of the mechanism. The outer end of the slot 263 has a lateral extension 268, extending toward the ring 88 and slightly backward, whereby the slot structure has a generally L-shaped configuration as illustrated in Fig. 5. It will now be understood that as the end portion of the wire is brought around toward the twisting gear, e. g. from the position of Fig. 24 toward that of Fig. 25, the wire moves past the side edge 269 of the pusher, temporarily shifting the pusher sidewise by virtue of the slot extension 268. Thus the wire is enabled to clear the pusher and enter the slot 181 of the twisting gear, the pusher 260 returning to its position of Fig. 5 as soon as the wire has been carried past it. Thereafter at an appropriate time the air cylinder 267 is operated to expel the piston rod 266 and cause V-shaped notch 264 to engage the wire 150b, and likewise the wire 150a, forcing them positively to the very center of the twisting gear at the outset of the twisting operation. It will also be understood that the centering bar 252, which operates when the gear turns away from the position shown in Fig. 5, serves additionally in the manner described above to promote or maintain the centered relationship of the wires.

When the gripper returns to its starting or rest position as indicated in Fig. 25, it must pass under the standing part 150a so that the latter may be in position to enter the gripper jaws when they are released in a manner more fully explained below. As will be noted from Figs. 6 and 13 the gripper projects a considerable distance from the face of the ring 88, the jaw body portions 121 and 122 having sloping faces so that the standing part 150a of the wire may ride up, so to speak, to the outermost, central part of the gripper when the latter resumes its normal or rest position. This action tends to spring the wire 150a away from the face of the gripper. While the wire pushing bar 240 is designed to effectuate seating of the wire between the gripper jaws (Fig. 16), further means have been found desirable, above the gripper, to cooperate in urging the wire toward and into the desired position. Accordingly as shown in Figs. 4, 7 and 20 a hold-down bar 270 is pivoted to a plate 272 that is mounted in a projecting relation upon the supporting plate 80, the arrangement being such that the plate 272 somewhat overhangs the forward face of the ring 88 and the hold-down bar 270 is adapted to swing toward and away from the outer face of the plate 272. A screw 273 threaded in the bar 270 provides an adjustable stop which prevents the bar from closing the space between it and the plate 272 beyond a predetermined distance which is advantageously larger than the diameter of the wire 150. The bar 270 also has a slot 274 transversed by a long pin 275 which carries at its outer end a nut 276. A coil spring 277 is disposed under compression between the nut 276 and the bar 270, thereby urging the bar to the position of Fig. 20 with the stop 273 against the plate 272. The described parts are mounted so that the path of the wire from the wire tensioning or supply means 144, 145 to the normal position of the gripper and likewise to the twisting gear, passes between an end portion of bar 270 and the face

of the plate 272. By reason of the setting of the stop 273 the wire passes loosely between the described elements thus easily re-entering this space as it is drawn around in the manner illustrated in Fig. 23. When the gripper is thereafter brought under this standing part of the wire, forcing the latter outwardly as explained above, such outward motion of the wire rocks the bar 270 outward against the spring 277. The latter, however, causes the bar to hold the wire down, against its springing out beyond the face of the gripper jaws, and thus keeping the wire close to the jaws and in place for it to be seated between them by the pusher element 240.

The plate 272 serves the further and advantageous function of aligning the gripper assembly as it comes to a stop after a revolution of the ring 88. In carrying the wire around the pipe, the gripper jaws are apt to become cocked out of perpendicular relation to a radius of the ring. As shown in Figs. 12, 13, 24 and 25, the tapered end edge of the gripper jaw 121, will strike against and slide along the lower, straight edge of the plate 272 so that on the final travel of the returning gripper, the edge of the plate will cause the gripper to turn and thus come to rest with its upper edge squarely abutting the plate and with the gripping faces of its jaws aligned along a radius of the ring which makes a 45° angle with the vertical.

In order to arrest the ring 88 positively when it returns to its initial and terminal position (Fig. 25, being the same position as that of Fig. 21), a so-called gag-stop is provided, comprising a block 286 projecting from the rear or pipe-entering face of the ring 88 and a cooperating detent assembly mounted on the plate 80 and generally designated 282, these and associate instrumentalities being particularly shown in Figs. 3, 6, 8 and 9. The detent 282 has an end face 283 shaped and disposed to abut the block 286, when the detent is disposed, as shown in Fig. 8, in the path of the block. At its remote end the detent or stop bar assembly is pivoted to the plate 80 by a pin 284 which transverses a longitudinal slot 285 in the bar, the slot 285 permitting a short displacement of the detent, e. g. to the position of Fig. 8, as the arresting face 283 meets the block 286 and brings the ring 88 to a stop. The detent bar structure 282 normally tends, by gravity (or if desired by other means, not shown) to turn counter-clockwise about the pin 284 as seen in Figs. 3 and 8, and thus to assume a position in the path of the block 286. A member 286 projecting laterally from the detent structure is adapted to rest on the upper side of a block 287 which is mounted in appropriate guide structure 288 so that it can slide transversely of the detent bar, i. e. up and down as seen in Fig. 9. The guide structure 288 is mounted on the framework 192 associated with the twisting gear mechanism, such framework also carrying a similar guide structure 290 for a sliding assembly 292 which is arranged to move transversely of the frame 192, i. e. between the rack and piston rod assembly 183-195 and the described detent assembly. Intermediate the sliding structure 292 and the movable block 287, a connecting element 294 is provided whereby transverse motion of the structure 292 may be translated into vertical motion of the block 287. More particularly, the link element 294 has its ends shaped to constitute integral cylindrical portions 295, 296 which are seated in corresponding cylindrically-shaped sockets in the members 292 and 287. It will thus be seen

that when member 292 is moved, for example, from left toward right as seen in Fig. 9, the member 294, disposed at an angle of 45° will translate such displacement into upward motion of the block 287.

As shown in Fig. 6 the outer end 298 of the sliding device 292 has a partly beveled face and is adapted to ride, so to speak, against a lengthwise extending portion 299 of the rack 188. The 10 rack portion 299 for the most part is constituted with an outwardly projecting cam surface 300 so arranged, as shown in Fig. 6 (and being at the right-hand side of the portion 299 in Fig. 9, although not there seen), that when the piston rod 15 195 is moved to the right (Fig. 6) the surface 300 cams the device 292 away from the rack, shifting the link member 294 and moving the block 287 upwardly (Figs. 8 and 9). A spring 301 under compression urges the slide 292 against the side of the rack structure at all times. It will now be seen that a normal position of the 20 detent or stop assembly 282 is that illustrated in the drawings, i. e. in the sense that the detent lies in the path of the block 286, the plate 286 thus normally resting on the block 287 and the 25 position of the latter being governed by the seating of the slide 292 against the low portion of the rack surface 299. When the rack is displaced away from the position shown in Fig. 6, the high 30 portion 300 operates the described instrumentalities, 292, 294 and 297 so as to elevate the latter of them and thus raise the projection 286 of the stop assembly. In consequence the stop assembly 282 is swung clockwise (Fig. 8), moving the 35 face 283 away from the block 286 and releasing the ring 88 for a new cycle of rotation. Thereafter when the rack returns to the position of Fig. 6, the parts assume their original position and the detent is reinstated in the path of the block 40 286 on the ring. To facilitate the withdrawal of the stop assembly 282 from a rest position, the assembly is provided with a spring-biased knuckle 302, which is normally adapted to maintain a rigid position, for detent action, but is adapted 45 to break slightly when the end face 283 is moved across and away from the block 286.

It has been explained that the twisting gear 170 effectively twists the wires 150a and 150b together at two places, i. e. on each side of the gear, the shearing blades 214, 215 then severing the wires at the lower side of the gripper jaws and at the underface of the twisting wheel. As a result a short piece or slug of twisted wire remains in the twisting gear, i. e. after the wire 50 controlling elements 228, 224 and 240 have been withdrawn and at a time when the mechanism 55 may be ready to initiate a new bundling operation upon another assembly of pipe. In order to remove this slug, a kicker device is provided as shown in Figs. 8, 12, 14, 21 and 22. This device 60 comprises a kicker arm 310 mounted on a shaft 311 which has an outer or enlarged portion 312 and which is biased against rotation by a torsion spring 313, the spring 313 being connected between the shaft portion 312 and a sleeve 313a that is seated in the ring 88. The shaft structure 311, 312 is adapted to turn within the sleeve, but is thus biased against such turning, i. e. biased 65 against turning in a clockwise direction (Fig. 12) by the spring. A stop 313b prevents rotation of the assembly in a counter-clockwise direction beyond a predetermined point as likewise shown in Fig. 12.

The kicker arm 310 projects from the forward 70 or pipe-leaving face of the ring, while the shaft

313, projecting from the opposite ring face carries an actuating arm 314 disposed to abut a cam block 316 that is placed on the supporting plate 80. It will be seen that the kicker arm 310 is thus arranged to swing in a plane parallel to the face of the ring and has a plate-like terminal portion 318 of such dimensions and position that it may sweep through the slot of the twisting gear. The kicker structure is located on the ring at a position slightly spaced from the gripper 110, behind the latter in the direction of its travel as the ring turns, the block 316 being disposed to engage the arm 314 only when the kicker arm 310 has moved about half way past the twisting gear. The normal position of the kicker arm, i. e. as in Fig. 12, is such that it sweeps across the upper face of the twisting gear, but as it reaches the center of the gear, the arm 314 strikes the block 216. The camming action of the latter swings the kicker arm clockwise so as to bring it down into and through the slot of the twisting gear whereby the slug 320 (Figs. 21 and 22) is thrown out of the slot and falls clear of the mechanism, e. g. to an appropriate discharge chute or the like, not shown. In this manner, the slug 320 is positively removed from the twisting gear at the initiation of a new cycle of operation of the wrapping mechanism.

As explained hereinabove the assembly of pipes are initially lifted from the rollers 48—50 by the plates 160 actuated by the cylinders 164, so that the wrapping operation may take place with the pipes clear of the rollers. Additional means for effecting further elevation of the pipe assembly are preferably provided, to permit a more satisfactory wrapping operation and to prevent undue tension on the wire in the early stages of such operation. To that end the bar 163 which carries the lift plate 160 and the cylinder 164 (Figs. 3 and 4) is pivoted at one end 330 to the base of the wrapping device and at its opposite end carries a cam follower roller 332 which rides on the surface of a cam 333. The cam 333 is mounted on a shaft 334 to which is secured a pinion 335, the shaft being journaled in an appropriate part of the mechanism base. The pinion 335 meshes with a vertically reciprocable rack 336 connected at its upper end to the piston rod 337 of an air cylinder 338, which is likewise mounted on a part of the supporting structure. In consequence when the air cylinder 338 operates to drive the rod 337 downwardly as seen in Figs. 3 and 4, the rack turns the pinion 335 and correspondingly rotates the cam 333. The parts are illustrated with the cam follower 332 resting on the lowest part of the cam. As the rack 336 descends, the structure of the cam, involving a fast rise portion 340, is such as to move the outer end of the bar 163 rapidly upwardly for a predetermined distance. The shape of the cam then provides a short dwell and a more gradual further rise, as by the portion 341 of the cam surface, whereby the end of the bar is carried to an uppermost locality. The plate 160, supported on the bar 163, and likewise the assembly of pipes are correspondingly raised by progressive stages during the operation of the rack 336. As explained hereinbelow, the motion of the piston rod 337 is arrested at this point; then on its return stroke, under appropriate control, the bar 163 and lift plate 160 are lowered to the original position, e. g. as shown in Figs. 3 and 4.

More specifically, the supplemental elevation

afforded by the cam arrangement and the swinging bar 163 is carried out in part as the gripper brings the wire around under the assembly of pipes (Fig. 23) and in further and final part as the twisting gear performs its twisting cycle. If the pipes were held at the lowermost position throughout the wrapping operation, either the wire would tend to be too loose at the time of final twisting, or would require an inordinately long twist in order to tighten the end portion and standing portion snugly together against the bundle. It will now be seen that by raising the pipe substantially as the wire passes around it substantial slack is provided in the wire (Figs. 23 and 24), which is available to be taken up as the gripper eventually reaches its terminal position (Fig. 25). This action permits the wrapping operation to be effectuated with a loop of minimum size, and at the same time relieves the gripper jaws of unnecessary strain such as might be caused by snubbing the wire against the underside of the pipe assembly during the intermediate stages of the revolution of the ring; any possibility of stripping the wires from the jaws at this time is consequently obviated. The final lift at the end of the operating cam surface is arranged to occur while the twisting gear is turning, so that the shortening of the wire portion between the gear and the bundle (occurred by twist) is substantially compensated by the further elevation of the bundle. It will be understood, of course, that the compensation is appropriately limited by the extent of lift so as to permit an effectively tight twist of the wires against the side of the pipe assembly.

As the gripper draws the wire around the pipe, for instance as it takes up the slack occasioned by the lifting operation described immediately hereinabove, there may be some tendency for the wire to lift the pipe from the supporting plate 160. To obviate this tendency a clamp element 350 is mounted to swing about a pivot 351 toward and away from the top of the pipe assembly and at one side, e. g. the pipe-leaving side of the wrapping mechanism. The clamp structure 350 has an actuating arm 352 pivotally connected to the piston rod 353 of an air cylinder 354. The normal position of the rod 353 keeps the clamp 350 in an elevated position, but at a suitable time, the cylinder is operated to move its piston rod upwardly (Fig. 4) thus swinging the clamp 350 counter-clockwise and down against the bundle of pipe supported on the plate 160. It will be understood that the supplemental clamp arrangement just described, is carried by the bar 163.

It has been explained that in the specific machine illustrated here many of the instrumentalities are actuated by air cylinders, controlled to operate at desired times in the wrapping and fastening cycle, it being understood that other driving devices may be alternatively employed, if desired. For control of the various air cylinders in the illustrated machine, suitable solenoid valves (shown by diagrammatic example in Fig. 26) may be provided, to control in corresponding fashion, the supply of air under pressure to one end or other of the cylinders for the desired displacement of their pistons and operated instrumentalities in one direction or the other. Since such valves and electrical controlling circuits therefor are generally known, details of the customary parts of same are omitted from the drawings; but to illustrate the interrelation between the several operated instrumentalities and the

control system, Fig. 26 shows the manner in which various electrical switches may be positioned and actuated so as to effectuate operations in the desired sequence and timing. Fig. 26 also illustrates certain control circuits and systems as representative examples of functional characteristics suitable generally for such parts of the apparatus. Fig. 27 shows a timing or operating chart for the machine and in effect further illustrates the scheme of connection between the switches and the several air cylinders or other driving instrumentalities actuated thereby through appropriate solenoid valves or means as explained above. Thus it will be understood in Fig. 26 that each described switch is arranged to actuate a corresponding element or set of elements of the machine in the manner further delineated in Fig. 27.

As will be apparent, Fig. 26 represents an extremely simplified view of certain operating parts. For clarity, the twisting gear 170 is shown as directly meshing with the rack 188 rather than through a train of gears; other parts of the mechanism have been similarly abbreviated. Certain primary controlling functions are effectuated by a plurality of cam actuated switches designated S-2, S-3 and S-4, respectively, adapted to be actuated by the high spots or lobes 360, 361 and 362 of cam wheels 364, 365 and 366 all mounted on shaft 75. The ratios of the gearing and chain transmitting parts between the shaft 75 and the main drive shaft 58 are conveniently such that the shaft 75 makes precisely one revolution while the ring 88 is making one revolution, i. e. the shaft 75 turns in exact synchronism with the ring 88. The several switches S-2, S-3 and S-4 (as likewise the switches S-5 to S-9 inclusive, below described) may be of a known, step-operating type, effective to change a circuit condition by displacement of a switch actuating member in a predetermined direction, the switch actuating member then being adapted to return to its original position, and the switch and circuit being adapted to remain in the modified or controlled condition until the switch is again actuated or the circuit is modified at another locality. Specifically, the switch S-2, S-3 and S-4 are conveniently arranged to operate at successive points in the single revolution of the shaft 75. For example, the parts may be arranged so that the normal or rest position of the cams is with the lobe 362 in a locality where it has just passed the switch S-4, the switch S-2 being disposed to operate when the shaft has travelled 180° from such locality, the switch S-3 to operate upon travel 90° further and the switch S-4 being then adapted to operate at the completion of the single revolution.

For initiating each cycle of the operating machine, a limit switch or flag stop switch S-1 may be provided at the extreme pipe-leaving end of the entire apparatus. The switch S-1 has an operating member 370 disposed in the path of the pipe and adapted to be swung to actuate the switch S-1 when the lead end of an entering bundle of pipe has travelled through the machine and the bundle is in a desired position for wrapping operations. Accordingly, it will be seen that the switch S-1 is actuated in response to the advance of pipe to it, and may serve to initiate the actual wrapping and fastening cycle.

Further control switches include a switch S-5 disposed to be actuated by the detent or gag-stop device 282 when the same is struck by the block 280 and moved backwards relative to pin 284. The switch S-5 is thus actuated at or preferably

slightly before the instant that the ring 88 comes to rest. The driving bar 232 for the wire control bar 224 has a lateral projection 372 arranged to engage and operate a switch S-6 when the wire control bar is moved into its outward position, i. e. when the wire control bar and associated finger 220 have completed their travel to the left under the drive of the cylinder 235.

A pair of switches S-7 and S-8 are arranged to be operated in accordance with the position of the rack 188, for example by means illustrated (for simplicity) as a switch actuating block 374. The switch S-7 is positioned so that it is engaged by the block 374 when the rack has completed about three-fourths of its travel from its extreme outer position to the opposite limit of its path. Similarly the switch S-8 is arranged to be actuated by the block 374 when the rack has completed its inward travel, i. e. has reached the last mentioned limit of its path. It may be explained that the movement of the rack from its outer to its inner position provides the stroke during which the twisting gear is turned for actual twisting function; in consequence switch S-7 is actuated just before the twisting gear is about to make its final twisting revolution, and the switch S-8 is actuated at the end of the twisting cycle.

The lever 206 which actuates the shearing head carries a projection 376 which is adapted to engage and actuate switch S-9 at the end of the shearing stroke, the projection 376 moving back away from the switch when the cylinder 210 expels its piston rod and withdraws the lever 206 and the shearing blades 214, 215 from their outermost (cutting) position. A further switch S-11 is disposed to be actuated by the projection 372 on the wire control operating rod 232 when the wire control parts are in, or have moved back to their normal or withdrawn position. More specifically the switch S-11, which is a safety switch and is connected in the circuit of the magnetic clutch 60 controlled by the flag stop switch S-1 as diagrammatically shown, is adapted to be maintained in a circuit-closing position only when the piston rod 234 is fully retracted, i. e. to the right as seen in Fig. 26.

Although, if desired, different types of switch contact structures and electrical systems, e. g. systems (of known type) involving single-throw switches and relay contacts, connected to control holding relays and the like, may be employed in lieu of the contact structures mentioned herein and schematically represented in Fig. 26, the latter arrangements will serve to illustrate, by way of example and in a simplified manner, the character and function of the automatic control by which the various primary elements of the machine may be operated.

Referring now to Fig. 27, which illustrates the scheme of control connections as well as the sequence and inter-relation of various operations, it may be first noted that switches S-1 to S-4 inclusive govern operations of the entire machine and are adapted to control simultaneously, by a parallel connection, certain instrumentalities in each of the wrapping mechanisms 40, 40a, 40b (and others, if any). Switches S-5 to S-9 inclusive are individual to each mechanism and only control certain parts in it, although the identity of structure and function of the mechanisms is that the operations so controlled occur in at least substantially close synchronism throughout the entire apparatus.

In Fig. 27, the left-hand column designates various actuated or operated parts of the ap-

21

paratus, the parenthetical reference number in each case identifying the air cylinder, solenoid or other actuating element that is (in nearly all cases) directly controlled and that brings about the stated operation. The shaded horizontal bands (also further identified by the letters A to M inclusive) represent the condition of the several parts during a complete cycle of operation extending in time from left to right; the uniformly low portions of the bands represent inactive, withdrawn or other non-operating condition of the elements, while the high portions indicate operation and in appropriate instances the magnitude or extent thereof is shown, to a rough approximation, by the height of the last-mentioned portions. As stated, time runs in the direction of the arrow 380. The several control switches are indicated across the top of the diagram. The vertical dotted lines depending from S-1, S-2, etc. represent the control connections, such connections being specifically indicated by a small circle at the intersection of each vertical line with the upper boundary of the band corresponding to the controlled instrumentality. As will be noted, the dotted vertical lines lack such connecting circles where they cross upper boundaries of bands relating to elements for which the corresponding switches have no direct controlling relation. In the following description the several controlled elements are identified by the reference numbers used for them in other figures and also by the letters A, B, C, etc. designating the corresponding bands or control circuits on the diagram, Fig. 27.

Thus the so-called flag-stop switch S-1, when operated by the leading end of a bundle of pipe 112, energizes the magnetic clutch 60 (A) and also, in each wrapping mechanism, initiates operation of the air cylinder 164 (B) to lift the pipe assembly from the conveyor rolls 48, 49, 50. The next operated controls are the cam switches S-2, S-3 and S-4, also called drum switches since the cam wheels 364-6 are conveniently integrated in a single drum as shown in Fig. 1. The switch S-2 initiates operation of the air cylinder 193 (C), forcing its piston rod 195 outward until the twisting gear 170 has made the predetermined number of revolutions (e. g. 4½) in the first or non-twisting direction; switch S-2 also operates the air cylinder 354 (F) to move the clamp 350 down on the assembly of pipe 112. Switch S-3 controls the air cylinder 338 (D), causing it to commence driving the rack 336 downward; the cam 333 thus promptly elevates the pipe 112 a considerable further distance, but the downward motion of the piston rod 337 continues until some time after the ring 88 stops turning, preferably so that the final, highest lift of the bundle occurs only as the twist of wires 150a, 150b is effectuated.

Switch S-4 deenergizes the magnetic clutch 60 (A), and also energizes the solenoid 139 (H) to open the gripper jaws. Switch S-5, operated by the gag stop device 282, initiates operation of the air cylinders 235 (E) and 267 (I), the first moving the wire control and retaining members 240, 224 and 220 against or around the wires, and the second causing the centering pusher 260 to force the wires to the center of the twisting gear. Complete outward throw of the wire control members by the cylinder 235 operates the switch S-6, which exerts reverse control of the air cylinder 193 (C), initiating return operation of its piston and thereby causing the rack 188 to move inward until the twisting gear

22

170 has turned 4½ times in the second or twisting direction. The switch S-6 exerts similar reverse control of the cylinder 354 (band F), so that the bundle clamp 350 rises or releases its hold on the pipe while the twisting gear is thus operating. As the rack 188 completes about 75% of its inward movement, it operates switch S-7, which initiates the return stroke of the cylinder 235 (E) so that the wire control bar 224 and the pusher bar 240 are effectively withdrawn from engagement with the wires at least by the time the twisting gear begins its last half revolution. Switch S-7 also initiates the return stroke of the air cylinder 267 (I), moving the centering pusher 260 back to its original position.

At the very end of the inward travel of the rack 188 and thus upon completion of the twisting step, the switch S-8 is operated to initiate operation of the cylinder 210 (G), so that its piston is retracted and the shearing head 203 is moved out for the wire cutting stroke; switch S-8 also opens the circuit of the solenoid 139 (H), deenergizing the same to close the wire gripper. As the shearing lever reaches the end of the cutting stroke it actuates the switch S-9, which controls the cylinders 164 and 338 (B and D) for their retracting, i. e. return strokes, and which also initiates the opposite operation of the cylinder 210 (G), forcing out its piston rod 202 and withdrawing the shearing blades. The described return strokes of the cylinders 164 and 338 lower the bundle of pipe 112 to the conveyor rolls, for delivery from the machine.

Certain other operating characteristics of the machine are also illustrated in Fig. 27, the timing and other direct relationship of these further elements to the operations delineated in the upper part of the diagram being indicated by vertical dot and dash lines between the corresponding points on the upper boundaries of the related horizontal bands. Thus the gag stop release, i. e. the sliding assembly 292-294-287 controlled by the rack cam surface 300 (J), stands normally in an actuated position where it holds the stop or detent 282 out of the path of the block 280 on the ring 88. This gag stop release is disengaged, by the end of the cam surface 300, just before the rack 188 (or cylinder 193, element C), completes its outward stroke. The gag stop may thus operate to arrest the ring 88, but it is shifted back to inoperative position when the release device is again actuated, i. e. just after the rack cylinder 193 has begun its return stroke.

The scrap kick-out device 310 is controlled by the travel of the ring 88. Thus shortly after the magnetic clutch 60 (A) has been energized, the ring carries the kicker actuating arm 314 (K) past the cam block 316, thereby swinging the kicker through its brief cycle of operation. Finally it is to be noted that the actual advance of pipe by the driven conveyor rolls 50 (L) is related, at least indirectly, to the initial and terminal control points for the machine; for example, these continuously turning rollers cease advancing the pipe assembly 112 as soon as it is lifted from them by the plate 160, raised by the cylinder 164 (B). The rollers subsequently resume their pipe-conveying function, i. e. when the cylinders 164 and 338 (B and D) have completed their return strokes and the finished bundle of pipe is re-deposited on the rollers.

It should be appreciated that the diagram (Fig. 27) is not drawn to an exactly linear time

scale; the equal horizontal distances between the successive vertical lines have simply been adopted for clarity and brevity of illustration, and do not by any means indicate that the actual intervals of time between these successive control operations are equal in the machine. For instance, as will be apparent from Fig. 26, the time between the actuation of switch S-1 and that of switch S-2 permits a full half revolution of the ring 88, and is thus twice the time between operations of S-2 and S-3, and likewise twice that between S-3 and S-4. The last-mentioned interval is long, however, relative to the brief period elapsing between the actual machine operations that control S-4 and S-5 in succession at the end of the ring travel. The time from the operation of S-6 to the operation of S-1 is equal to 75% of the return movement of the twisting gear rack 188, and is consequently three times the interval between the operations of S-1 and S-8, here indicated as occupying one unit on the time axis of the chart. Moreover, the steps of wrapping 382, twisting 384 and cutting 386 actually follow each other with little or no delay. In these and other respects the chart should only be taken as showing the simple fact of succession in time for the operations noted, rather than actual values of time between them.

The safety switch S-11 (element M) serves to avoid damage to the wire control fingers 220, 224 and other parts, such as might occur if the machine were started before the compressed air supply is turned on. When the air is turned off, for example, these fingers tend to drift forward and might be broken by rotation of the ring 88. However, the switch S-11 is closed only if the fingers are fully retracted—as occurs when the piston rod 234 is drawn back by positive air pressure on the return side of the cylinder 235—so that the magnetic clutch 60, in circuit with switch S-11, cannot be engaged unless the fingers are out of the way and unless, in effect, the air is turned on. In Fig. 27 it is assumed that the air supply is effective at all times; the band M simply illustrates the mechanical relationship of S-11 to the cylinder 235 and the idling operation of the switch as the wire control fingers pursue their intended cycle.

As stated, Fig. 26 shows, in simple diagrammatic form, a circuit effecting the control of the magnetic clutch 60, connected at x-x, by the switches S-1, S-11 and S-4, the latter being duplicated in phantom view and both S-1 and S-11 including representation of other simultaneously operated contacts to provide the additional controlling functions set forth in Fig. 27. Fig. 26 similarly indicates, as an example of others, the circuit of switches S-2 and S-3 for control of cylinders 193 and 354 piped in tandem, by means of a solenoid valve 378. For the circuit, the switch S-6 is duplicated in phantom with schematic detail such as may characterize all other switches S-1 to S-5 and S-7 to S-9, i. e. to afford a switch that changes the circuit when the switch-operating arm is thrown in one direction, the switch contacts remaining so changed until the arm, after moving itself back, has been again thrown in the same direction. It will also be noted that the illustrated example of a way to provide the two-station on-off control which is employed in all circuits involves wiring the sets of switch contacts as single pole, double throw switches. Although if an abundance of caution so dictates, switches identical with S-11 may be

included in each of the wrapping mechanisms 40, 40a and 40b and all of them connected in series with the magnetic clutch 60, the drawing, for simplicity, shows only one such switch (to serve the described purpose of safety) in the starting control circuit.

For additional safety and reliability, certain ancillary devices may be included in the machine, such as a stop or brake 388 (Fig. 26) which physically arrests the pipe in wrapping position, the stop 388 being actuated by a solenoid 390 or other means, under control of switch S-1. In order to prevent rebound of the ring 88 (in each of the wrapping mechanisms) when it causes the gag stop 282 to strike the block 280, a pair of one-way or anti-back up clutches 391, 392, fragmentarily shown in Fig. 26, may be carried on the main drive shaft 58 at either side of the magnetic clutch.

The manner of operation of the entire apparatus has in effect been described above, but may be conveniently summarized here. An assembly of pipe 112 to be bundled is fed endwise into the machine (e. g. at the right hand end of Figs. 1 and 2), so as to rest on rollers 50, 49 and so on. The rollers 50, continuously turning, advance the assembly 112 until its leading end strikes and operates the flag-stop switch S-1. As a result, the plates 160 lift the assembly from the rolls (interrupting the lengthwise motion of the assembly) and each of the rings 88 commences to revolve, providing switch S-11 is closed. In each of the wrapping mechanisms 40, 40a and 40b, the gripper 110, now holding the very end of the wire 150, thus commences to move counter-clockwise (as seen in Figs. 4, 12 and 21 to 25) to carry such end of the wire away from the original gripper position of Fig. 21, around the pipe assembly and back to the same, rest position indicated in Fig. 25; during this single revolution of the gripper, it turns in its bearings as necessary to suit the direction in which it is actually pulling the wire at each instant, and it in fact makes one half revolution on its own axis while the ring goes around. At an early stage in the ring travel, the kick-out arm 310 is caused to wipe through the slot of the twisting gear, removing the wire slug remaining from the previous operation of the machine. By the time the gripper is half-way around, a considerable length of wire has been drawn through the tensioning means 144—145 (which may also be referred to as wire supply means), and the withdrawn wire has been brought against the underside of the pipe assembly. Likewise by this operation the standing part 150a of the wire has been pulled into the slot of the twisting gear 170, which was facing as shown in Figs. 21 to 23. At this point, the rack 188 is moved outward, rotating the twisting gear through four and one half turns so that it stops facing in the other direction (Fig. 24); since there is only one wire in the gear, no actual twist is made. When the gear starts this course of rotation, the centering element 252 is engaged and shifted by the wire, and causes the latter to occupy a central position in the gear.

At the same time, the bundle clamp 350 is moved down on top of the pipe assembly. The gripper continues to be carried around by the ring, and at about the three-fourths position (Fig. 24) the cam 333 moves through its rapid-rise section, causing a substantial further elevation of the pipe assembly and permitting some slack in the wire so that the gripper can draw the end on around without having to pull any

considerable further portion from the supply means and against frictional contact with the underside of the pipe assembly. At or about this stage of the operations, the gag stop release device is withdrawn, permitting the gag stop or detent assembly 282 to fall into the path of the block 280 on the ring. The ring continues its travel, finally bringing the gripper 110 back to the original, rest position (Fig. 25) and causing the adjacent end portion 150b of the wire to slide into the slot of the twisting gear 170 (now facing to receive such portion of wire). As or very slightly before the gripper comes to rest, the magnetic clutch is deenergized (interrupting positive drive of the ring) and the solenoid 139 opens the jaws of the gripper, freeing the end of the wire. The ring is actually and positively stopped by the gag stop or detent 282, whereupon the centering pusher 260 is actuated to center the two wires 150a, 150b fully in the twisting gear. The bars 240 and 224 are also moved into engagement with the wire.

The previous rotation of the gear 170 has already caused the wire 150a to lie on the flat side 221 of the finger 220; the pusher 260 is now pushing the wire 150b against the wire 150a (and against the same side of the finger) so that both wires tend to be disposed as in Fig. 15, the gripper 110 having already moved under the wire 150a, putting the latter in position to enter the open jaws. The pusher bar 240 thus pushes the wire 150a into the jaws (with wire 150b still behind it); the advancing bar 224 and finger 220 straddle the two wires and hold them, one behind the other, in the intervening narrow slot which is just wide enough to clear a single wire diameter.

As soon as the wires are so held, at a position lying between the gripper and the twisting gear but spaced from both, the twisting gear rack starts inward and effects rotation of the twisting gear, for four and one half revolutions. This operation twists the two wires together both above and below the gear, the disposition of the parts being such that the twist on the side toward the pipes 112 is made effectively tight against the latter while taking further into account the slight additional rise of the pipe assembly by the final motion of the cam 333 (advantageously effected while the twisting gear is turning—or at least, no later), such rise compensating for the shortening of the wires caused by the twist, in such fashion that they can be made reasonably taut even at the beginning of the twist.

Just after the rack 188 starts its travel to turn the twisting gear as described above, the gag stop release is reset to clear the ring 28 for a subsequent cycle of rotation, and when the rack has completed about three-fourths of its travel, the centering pusher 260 is retracted and likewise the pusher bar 240, the wire control bar 224 and the finger 220. It will be remembered that the bar 224 and finger 220 are adapted to swing down toward the twisting gear as the twist above the latter shortens the wires in the intervening region; while such shortening tends to pull the original end of the wire 150b down out of the gripper jaws, the withdrawal of the holding elements 220, 224 before the gear 170 makes its last half-turn enables this wire end to whip around and spring fully clear, thus insuring that only the standing part 150a remains in the jaws. The bundle clamp 350 has already been raised clear, i. e., as the twisting progressed.

At the very end of the twisting, which leaves the gear 170 with its slot facing in the opposite direction, ready for a subsequent wrapping cycle, the gripper jaws close on the wire portion 150a and the shear head 200 moves in to sever the wires at the underside of the twisting gear (leaving the twist in place adjacent the bundle) and also to sever the wire 150a just below the gripper, from which the end of wire 150b has already been removed. It will be understood that on completion of its function the retraction of the wire control bar 224 carries it back under the shear blade 214 (Figs. 15-17), so that it is out of the way when the entire structure 200 is advanced to cause the shear blade to cut off the wire; the finger 220, somewhat retracted by the bar 224, is then also adapted to be pushed back against its spring 230 to the extent that it may meet the wire or other obstacle when the shear blade is projected.

As a result of these operations each wrapping mechanism has passed a single loop of wire around the pipes and has effectuated twisting and cutting operations so as to produce a fully tightened loop with its ends securely twisted together and thus fastened in an effectively permanent form. Upon the end of the shearing stroke in each mechanism, the shear blades are retracted to their original position and the elevator plate 160 and cam 333 are operated in a reverse direction to deposit the pipe bundle again on the rolls 48, 49, 50. In consequence the last-mentioned rollers promptly carry the bundle along endwise and out of the machine, thereby delivering a finished bundle of pipe which is tightly wrapped with wire at a plurality of places along its length, each such wrapping being securely and permanently fastened. At the same time all of the parts have been restored to their original positions or conditions (the flag-stop 370 turning back when the trailing end of the bundle has passed), a fresh end of wire is held in each gripper 110, and the machine is ready to repeat the cycle with a new group of lengths of pipe.

It will now be seen that the apparatus efficiently satisfied the several objects described at the outset of this specification, and with various further advantages, accomplishes the desired bundling of the pipes in a rapid and yet thoroughly reliable manner. The entire operation is automatic, even being initiated in response to the presence of pipe in position for wrapping; the resulting bundles are uniform and secure, requiring no manual twisting or adjustment of wires; and the machine is peculiarly free of tendency to break the wire or to become out of order in respect to its component instrumentalities.

It is to be understood that the invention is not limited to the specific structures herein shown and described, but may be embodied in other forms without departure from its spirit.

I claim:

1. In an apparatus for bundling elongated articles with wire, in combination, a plurality of spaced devices for wrapping wire about an assembly of articles at correspondingly spaced localities along said assembly, each of said devices comprising structure of upright annular shape defining a central opening adapted for receiving the assembly when advanced endwise into said opening, said structure comprising means for carrying wire around the received assembly to wrap the assembly, movable means arranged to define an assembly-receiving path which extends along the

wrapping devices through the openings thereof and in alignment with said openings, for advancing said assembly endwise along said path into and through the openings of said wrapping devices in succession, to displace said assembly into position simultaneously within the openings of all said devices for operation thereof at said localities, means for continuously driving said movable means in a single direction corresponding to a predetermined direction of advance of the assembly by the movable means toward and into said position, means shiftable relative to said movable means for separating said assembly from the movable means, to support the assembly during operation of the wrapping devices, and means timed with the wrapping devices and operable upon completion of the wrapping operation, for reversely operating said shiftable means to redeposit the assembly on the movable means, said movable means being constructed and arranged, under the continuous drive of said driving means, for advancing the assembly endwise out of the openings of the wrapping devices in succession, in the aforesaid predetermined direction.

2. In apparatus for bundling elongated articles with wire, in combination, a plurality of devices for wrapping wire about an assembly of articles, each of said devices having an opening to receive such assembly and said devices being respectively disposed to provide wrapping at localities spaced lengthwise of the assembly, roller means for moving such assembly endwise through the openings of the devices, into predetermined position, co-operating means adapted to engage the assembly, for lifting the same from the roller means, into predetermined elevated position suited for operation of the wrapping devices, and means timed with the wrapping devices to elevate the assembly further during the wrapping operation of said devices, to facilitate tight wrapping of wire.

3. In apparatus for bundling elongated articles with wire, in combination, an elongated supporting structure, a plurality of devices for wrapping wire about an assembly of articles, means adjustably mounting the devices on the supporting structure, to permit lengthwise adjustment of the spacing and position of said devices, movable means for advancing such assembly of articles endwise along said supporting structure into position for operation of said devices, and means associated with the devices for separating the assembly from the movable means, to support the articles during wrapping operation.

4. In apparatus for bundling elongated articles with wire, in combination, an elongated supporting structure, a rack extending lengthwise of said structure, a plurality of devices for wrapping wire about an assembly of articles, said devices being supported by said structure and each having pinion means adapted to mesh with said rack whereby the position and spacing of said devices may be adjusted by operation of said pinion means, and means for advancing such assembly of articles into position on said structure for wrapping operation of said devices.

5. In apparatus for bundling elongated articles with wire, in combination, an elongated supporting structure, a rack extending lengthwise of said structure, a plurality of devices supported by said structure for wrapping wire about an assembly of articles, each of said devices having an opening to receive such assembly disposed lengthwise of

the structure and each of said articles having pinion means adapted to mesh with said rack, whereby adjustment of the position and spacing of the devices lengthwise of the structure may be effected by operation of said pinion means, a plurality of roller means respectively associated with the devices and movable therewith, each roller means being rotatable for displacing such assembly of articles lengthwise of the structure through the openings of the devices, and a plurality of supporting elements respectively associated with the devices and adapted to engage an assembly of articles positioned in the openings, for elevating such assembly from the roller means, to a position suited for wrapping operation of the devices.

6. In apparatus for bundling elongated articles with wire, in combination, means for supporting articles to be bundled, wire supplying means, means including a releasable gripper and means for displacing the gripper along a path around the articles, for carrying the end of a length of wire from said supplying means around the supported articles from a predetermined locality back to the same locality, so that the wire is passed around the articles, a rotatable device at said locality between the gripper and the articles, said rotatable device having a wire-receiving opening and being first disposed to receive a part of the wire therein at an intermediate stage of its passage around the articles by the carrying means, means for displacing said rotatable device, after it has received the wire as aforesaid, to a position for receiving, in said opening, another part of the wire as the latter is brought back to said locality by the carrying means, and means for turning the rotatable device while both parts of the wire are retained therein, to twist said parts together, said rotatable device being disposed to receive said wire parts in parallel assembly, for twisting, with the end of each part that is nearest the remainder of the wire between said parts, being disposed at the same end of said parallel assembly.

7. In apparatus for bundling elongated articles with wire, in combination, means for supporting an assembly of articles to be bundled, gripper means adapted to engage a wire in the vicinity of its end, for drawing said wire from a wire supply, means for moving the gripper means in a path which extends from a predetermined position, around the supported articles, and which terminates at said position, to pass the wire around the articles, means operative upon completion of operation of said gripper-moving means, for fastening a portion of the wire adjacent its end, to a portion of the wire circumferentially spaced around the articles, and wire supplying means disposed outside the path of the gripper means, said gripper means being adapted to draw wire from said wire supplying means, said gripper-moving means including gripper-carrying structure movable around the supported articles, said gripper means being mounted to turn in said structure as the gripper draws the wire around the article from said wire supplying means, for bringing the end portion of the wire, after carrying said end portion around the articles, to a position extending from the articles in the same direction as the aforesaid other portion which is circumferentially spaced around the articles, said fastening means being disposed to receive both said end and aforesaid other portions of wire in side-by-side position extending radially outward from the articles, and

said fastening means comprising means for turning the said wire portions together to twist them at a locality between the fastening means and the articles.

8. In apparatus for bundling elongated articles with wire, in combination, means for supporting an assembly of articles to be bundled, means providing a wire supply, gripper means adapted to engage a wire in the vicinity of its end, for drawing said wire from said wire supply means, means for moving the gripper means in a path which extends from a predetermined position, around the supported articles, and which terminates at said position, to pass the wire around the articles, said wire supply means being disposed outside said path, and means operative upon completion of operation of said gripper-moving means and adapted to receive portions of the wire respectively near its end and circumferentially spaced around the articles, for twisting said portions together, said gripper-moving means including gripper-carrying structure movable around the supported articles, said gripper means being mounted to turn in said structure and thereby being adapted to reverse its disposition in the structure as said gripper means draws wire around the articles during its travel in the aforesaid path, said gripper means being adapted in its reversed position for similarly engaging wire from the wire supply means, whereby a succeeding wrapping operation may be initiated with the gripper means in said reversed position.

9. In apparatus for bundling elongated articles with wire, in combination, means for supporting an assembly of articles to be bundled, means providing a wire supply, gripper means adapted to engage a wire in the vicinity of its end, for drawing said wire from said wire supply means, means for moving the gripper means in a path which extends from a predetermined position, around the supported articles, and which terminates at said position, to pass the wire around the articles, said wire supply means being disposed outside said path, and means operative upon completion of operation of said gripper-moving means and including a rotatable member which is disposed intermediate the aforesaid position and the supported assembly and which is adapted to receive portions of the wire respectively near its end and circumferentially spaced around the articles, for twisting said portions together, said gripper-moving means including gripper-carrying structure movable around the supported articles, said gripper means being mounted to turn in said structure and thereby being adapted to reverse its disposition in the structure as said gripper means draws wire around the articles during its travel in the aforesaid path, said gripper means being adapted in its reversed position for similarly engaging wire from the wire supply means, whereby a succeeding wrapping operation may be initiated with the gripper means in said reversed position.

10. In apparatus for bundling elongated articles with wire, in combination, means for supporting an assembly of articles to be bundled, gripper means adapted to engage a wire in the vicinity of its end, for drawing said wire from a wire supply, means for moving the gripper means in a path which extends from a predetermined position, around the supported articles, and which terminates at said position, to pass the wire around the articles, and wire-twisting means comprising a radially slotted member ro-

tatable about an axis extending between the aforesaid position and the supported assembly, means for rotating said member in successively opposite directions about said axis, said member being adapted in one angular position to receive a remote portion of the wire in its slotted region as the gripper means draws the end of the wire around the articles, and said member being adapted in another angular position to receive a portion of the wire adjacent the end as the gripper means returns to the first-mentioned predetermined position, and means timing the member-rotating means so as to hold the member in the first angular position during at least an initial part of the travel of the gripper means around said path, said timing means operating said member-rotating means to dispose the member in its second angular position before the gripper means completes its travel in said path, and said timing means effecting wire-twisting rotation of the member after the gripper means has completed its travel in said path.

11. In apparatus for bundling elongated articles with wire, in combination, means for supporting an assembly of articles to be bundled, wire supply means, means including a device for gripping the end of a wire and means for displacing said device along a predetermined path completely around the supported assembly, for drawing wire from the supply around the supported assembly, said device moving in said predetermined path, said wire supply means being disposed outside said path, and means within said path and adapted to engage portions of both the standing part and the end of the resulting wire loop around the assembly, for fastening said portions together in tightened condition relative to the assembly, said gripping device being rotatably mounted on said displacing means, for rotation from a first position to a reversed position relative to the wire supply means, in response to the pull of the wire which the device draws from said supply means, as said device follows its aforesaid path of travel completely around the assembly of articles, and said gripping device comprising jaw means engageable, in each of said first and reversed positions of the gripping device, with wire extending from the supply means, for operation of said gripping device in its aforesaid reversed position upon completion of a displacement about the articles, to grip another end portion of wire, said gripping device being constructed and arranged to initiate its aforesaid travel, for a succeeding wrapping operation, in reversed position.

12. In apparatus for bundling elongated articles with wire, in combination, means for supporting an assembly of articles to be bundled, wire supply means, means including a gripping device movable in a path around the assembly and means for displacing said gripping device completely along said path from an initial position back to said initial position, for gripping the end of a wire to draw a loop of wire from said supply around the assembly, a wire engaging device adapted to receive the standing part of the wire as the end of same is drawn by the gripping device around the further side of the assembly from the supply, said wire engaging device being also adapted to receive an end portion of the wire upon completion of the loop by the gripping device, and means turning the wire engaging device, to twist said end portion and the standing part of the wire loop together, for fastening the loop in tightened condition relative to the

assembly, said wire engaging device being disposed between the wire supply means and the assembly of articles, said wire supply means and wire engaging device being initially and finally disposed substantially on a line that extends outwardly from said assembly of articles and that traverses said initial position of the gripping device, said gripping device in its said initial position, at both the beginning and the end of its said travel around the assembly of articles, being disposed between the wire supply means and the wire engaging device, and said wire engaging device being thereby adapted to twist said end portion and standing part together with the loop-adjacent ends of said portion and standing part arranged at the same end of the resulting twist.

13. In apparatus for bundling elongated articles with wire, in combination, means for supporting an assembly of articles to be bundled, wire supply means, means including a device movable in a path around the assembly, for gripping the end of a wire to draw a loop of wire from said supply around the assembly, a rotatable device having a wire-receiving slot and first disposed intermediate the wire supply means and the assembly so that the standing part of the wire enters said slot as the gripping device draws the end of the wire around the further side of the assembly, means for rotating said rotatable device, control means for actuating said rotating means to turn the slot in an opposite direction after receiving said standing part of the wire, so that an end portion of the wire is also received in said slot as the gripping device completes the loop, and control means operated on completion of the travel of the gripping device, for actuating the rotating means to turn the wire-receiving device and thereby twist the standing part and end portion of the wire together intermediate the receiving device and the assembly, said rotatable device being disposed to receive said standing part and end portion in parallel association, for twisting, with the ends of said part and portion that are nearest the loop being disposed at the same end of said parallel association.

14. In apparatus for bundling elongated articles with wire, in combination, means for supporting an assembly of articles to be bundled, wire supply means, means including a device movable in a path around the assembly, for gripping the end of a wire to draw a loop of wire from said supply around the assembly, a wheel having a wire-receiving radial slot, disposed intermediate the wire supply means and the supported assembly and rotatable on an axis at an angle to said assembly, said wheel being first disposed to receive the standing part of the wire in its slot as the gripping device traverses a first portion of its path, means to effect rotation of said wheel so that its slot faces in an opposite direction as the gripping device traverses a final portion of its path, said wheel being thereby disposed to receive an end portion of the wire in its slot, and means to effect rotation of said wheel for a plurality of turns, upon completion of travel of the gripping device, to twist the wires together intermediate the wheel and the assembly, said wheel being disposed to receive said standing part and end portion in parallel association, for twisting, with the ends of said part and portion that are nearest the loop being disposed at the same end of said parallel association.

15. In apparatus for bundling elongated articles with wire, in combination, means for supporting an assembly of articles to be bundled,

wire supply means, means including a device movable in a path around the assembly, for gripping the end of a wire to draw a loop of wire from said supply around the assembly, a wheel having a wire-receiving radial slot, disposed intermediate the wire supply means and the supported assembly and rotatable on an axis at an angle to said assembly, said wheel being first disposed to receive the standing part of the wire in its slot as the gripping device traverses a first portion of its path, means to effect rotation of said wheel so that its slot faces in an opposite direction as the gripping device traverses a final portion of its path, said wheel being thereby disposed to receive an end portion of the wire in its slot, means responsive to completion of travel of the gripping device, for opening the same to receive therein a portion of the standing part of the wire intermediate the wheel and the wire supply, cooperating means to effect disposition of said last-mentioned portion of the standing part of the wire in the opened gripping device, and means to effect rotation of the wheel whereby the standing and end portions of the wire are twisted together on both sides of the said wheel.

16. In apparatus for bundling elongated articles with wire, in combination, means for supporting an assembly of articles, a rotatable ring disposed to surround said assembly, wire supplying means outside said ring, a releasable gripper rotatably seated in the ring for engaging the end of a wire to draw the same from said supplying means, means peripherally engaging the ring to rotate the same, whereby the gripper draws the wire around the assembly to form a loop of said wire, and twisting means brought into play upon completion of said loop-forming rotation of the ring for twisting the end and standing portion of the wire together, said gripper turning to a reversed position in the ring as it draws the wire from the supplying means during a single revolution of the ring, and said gripper being adapted to engage another portion of wire in its said reversed position, whereby a subsequent wrapping operation can be initiated with the gripper in said reversed position.

17. The apparatus described in claim 16 which includes control means for the ring, to effect rotation of same carrying the gripper from a predetermined position back to the same predetermined position, said twisting device being disposed within the ring between said position and the supported assembly of articles and said twisting device comprising a rotatable member having a slot adapted to receive both said portions of wire, and which apparatus also includes means for severing the twisted wires adjacent the twisting device, whereby a twisted loop remains attached to the assembly of articles.

18. In apparatus for bundling elongated articles with wire, in combination, wire supplying means, a releasable gripper to hold the end of a wire, means including a movable supporting member, for moving the gripper around an assembly of articles, to draw the wire from said supplying means to form a loop around said assembly, and means disposed within the path of the gripper and adapted to receive both an end portion of the wire near the gripper and a portion of the standing part of the loop, for twisting said end and standing portions together, said wire supply means being disposed outside the path of the gripper, said gripper being adapted to turn in said supporting member to a reversed position,

as the gripper completes a revolution in said path, said supporting member, to a reversed position, to engage another part of the wire from said supplying means.

19. In apparatus for bundling elongated articles with wire, in combination, a releasable gripper to hold the end of a wire, means for moving the gripper around an assembly of articles, to draw the wire from a supply to form a loop around said assembly, said last-mentioned means being adapted to carry the gripper, while holding the first-mentioned wire end, to a position for engaging the standing part of the wire loop, means for arresting the moving means upon arrival of the gripper at said position, means for releasing the gripper, so that said standing part may be received in the latter, means to effect disposition of said standing part of the wire in the released gripper, means disposed within the path of the gripper and adapted to receive portions of said wire in said standing part and at said end, for twisting the wires together after said standing part has been received in the gripper, and means for severing the standing part adjacent the gripper, to leave a fresh end of wire in the gripper.

20. In apparatus for bundling elongated articles with wire, in combination, means for supporting an assembly of articles to be bundled, wire supply means, means including a device movable in a path around the assembly, for gripping the end of a wire to draw a loop of wire from said supply around the assembly, a wheel having a wire-receiving radial slot, disposed intermediate the wire supply means and the supported assembly and rotatable on an axis at an angle to said assembly, said wheel being first disposed to receive the standing part of the wire in its slot as the gripping device traverses a first portion of its path, means to effect rotation of said wheel so that its slot faces in an opposite direction as the gripping device traverses a final portion of its path, said wheel being thereby disposed to receive an end portion of the wire in its slot, means to effect rotation of said wheel for a plurality of turns, upon completion of travel of the gripping device, to twist the wires together intermediate the wheel and the assembly, and cutting means movable into operative engagement with the wire at a locality immediately adjacent the side of the wheel nearest the assembly, to sever both the end and standing portions of wire between the wheel and the twist effected thereby, said wheel being disposed to receive said standing part and end portion in parallel association, for twisting, with the ends of said part and portion that are nearest the loop being disposed at the same end of said parallel association.

21. In apparatus for bundling elongated articles with wire, in combination, means for supporting an assembly of articles to be bundled, wire supply means, means including a device movable in a path around the assembly, for gripping the end of a wire to draw a loop of wire from said supply around the assembly to a predetermined position, said wire supply means being disposed outside the path of said gripping device, a wheel having a wire-receiving radial slot, disposed intermediate the wire supply means and the supported assembly and rotatable on an axis at an angle to said assembly, said wheel being first disposed to receive the standing part of the wire in its slot as the gripping device traverses a first portion of its path, means to effect rota-

tion of said wheel so that its slot faces in an opposite direction as the gripping device traverses a final portion of its path, said wheel being thereby disposed to receive an end portion of the wire in its slot, means responsive to completion of travel of the gripping device to said position, for opening the same to receive therein a portion of the standing part of the wire intermediate the wheel and the wire supply, means to effect disposition of said standing part in the opened gripping device, means thereupon operated to effect rotation of the wheel whereby the standing and end portions of the wire are twisted together on both sides of the said wheel, and a pair of cutting means respectively movable into engagement with the wires at the side of the wheel which faces the assembly and at the side of the gripping device which faces the wheel, said cutting means having actuating means therefor operable upon completion of twisting operation by the wheel, to sever both wires at each of said localities.

22. In apparatus for bundling elongated articles with wire, in combination, means for supporting an assembly of articles to be bundled, wire supply means, means including a device movable in a path around the assembly, for gripping the end of a wire to draw a loop of wire from said supply around the assembly, means for opening said gripping device upon completion of its travel, cooperating means adapted to dispose a portion of the standing part of the loop of wire in said gripping device along with the aforesaid end portion, and means engaging adjacent parts of the end and standing portions of the wire, for twisting the same together, to fasten the wire in tightened condition relative to the assembly.

23. The apparatus described in claim 22 wherein the last-mentioned means comprises a rotatable, radially slotted member adapted to receive both the standing portion and end portions of the wire in its slotted region, said member being disposed within the path of the gripping device, intermediate the wire supply and the supported assembly, said apparatus also including wire engaging structure shiftable toward the rotatable member and means for so shifting said structure, to guide the standing part and adjacent end of the wire as the latter are drawn toward the aforesaid member by rotation thereof.

24. In apparatus for bundling elongated articles with wire, in combination, a releasable gripper to hold the end of a wire, means for moving said gripper around a group of articles to be bundled, to a predetermined terminal position, thereby to form a loop, a rotatable member disposed intermediate the path of the gripper and the assembly of articles, said rotatable member being spaced from the aforesaid terminal position of the gripper and said rotatable member being adapted to receive portions of the wire respectively adjacent its end and within the standing part of the loop, means for releasing the gripper upon arrival of the latter at said terminal position, so that a portion of the standing part of the wire may be received in the gripper, means movable into engagement with the standing and end portions of the wire intermediate the gripper and the rotatable member to hold said last-mentioned portions against rotation relative to each other, and means for rotating said member to twist the wire portions together both between the member and the articles and between the member and said movable means.

25. The apparatus described in claim 24 wherein the means movable into engagement with the wire portions comprises wire-holding structure and means mounting said structure for freedom of movement, when it is engaging the wires, in a direction toward the rotatable member, so that the structure may move in said last-mentioned direction as the twist effected by said member shortens the wires between said member and said structure.

26. The apparatus described in claim 24 wherein the means movable into engagement with the wire portions includes driving means for advancing and retracting said movable means, and control means for said driving means, timed with the rotatable member, for retracting said movable means before said member has effected its last half turn of rotation, so that the end portion of the wire is freed from the movable means and can be displaced from the gripper by the rotative motion of the rotatable member.

27. The apparatus described in claim 24 which includes an element movable toward the gripper when the latter is in the terminal position, for pushing a portion of the standing part of the loop into the released gripper, and common driving means for simultaneously moving said element and the aforesaid movable means respectively into pushing and holding engagement with the standing part of the wire loop.

28. The apparatus described in claim 24 wherein the movable means comprises a wire-engaging finger and a coacting bar, said finger being normally disposed to back up the standing part of the wire loop as the gripper moves to its terminal position, said bar having a portion shaped relative to the finger for holding wire portions between said bar and finger in a side-by-side alignment, and means for advancing said bar and finger together into position for so holding the standing and end portions of the loop.

29. In apparatus for bundling elongated articles with wire, in combination, a releasable gripper to hold the end of the wire, means for moving the gripper around the assembly from a predetermined position back to said predetermined position, to draw the wire from a supply to form a loop around said assembly, means disposed within the path of the gripper and adapted to receive both an end portion and a standing portion of the loop, for twisting said portions together, means disposed adjacent said predetermined position for backing up the standing portion of the wire, said gripper being adapted to receive said standing portion upon return to said position, means releasing the gripper for receipt of said standing portion, and means movable into engagement with the end and standing portions at a locality between the twisting means and said position, for holding said portions against rotation.

30. The apparatus described in claim 29 wherein the means for backing up the standing portion of the wire comprises a finger normally disposed adjacent the path of said standing portion between said position and the twisting means, and wherein the means for holding the end and standing portions comprises a bar having a surface shaped to coact with said finger and movable to engage said portions between the bar and finger.

31. The apparatus described in claim 29 which also includes wire supply means comprising a tensioning device disposed outside the path of the gripper and adjacent to said position, said

tensioning device being adapted for travel of wire through it as drawn by the gripper, and said tensioning device including means providing a tension on said wire and one way clutch means preventing reverse displacement of the wire.

32. In apparatus for bundling elongated articles with wire, in combination, means for supporting, in a horizontal position, an assembly of articles to be bundled, means for supplying wire at a locality spaced from the articles at a level above said articles, gripper means adapted to hold a portion of the wire supply by said supplying means, means for moving the gripper means in a path which extends from said locality, around the assembly and back to the vicinity of said locality, to pass the wire around the articles, and means cooperating with said gripper-moving means and operable during displacement of the gripper means in a portion of its path returning from the side of said assembly opposite to said locality, for displacing the assembly upward, to relieve tension on the wire as the gripper means traverses said portion of its path.

33. In apparatus for bundling elongated articles with wire, in combination, means for supporting an assembly of articles to be bundled, means supplying wire at a predetermined locality spaced from the assembly of articles, gripper means adapted to engage a wire in the vicinity of its end, for drawing said wire from the supply means, means for moving the gripper means in a path which extends from said locality, around the supported articles, back to the vicinity of said locality, and means cooperating with said gripper-moving means and operable as the gripper means moves through a portion of its path returning from the side of said assembly opposite to said locality, for displacing the assembly in a direction to dispose the assembly closer to said locality.

34. In apparatus for bundling elongated articles with wire, in combination, means for carrying wire around an assembly of said articles to form a loop, means adapted to engage both ends of the loop, to twist them together intermediate said means and the articles, and cooperating means for moving the articles toward said twisting means during operation of the latter, to compensate for shortening of the twisted wires during such operation, said twisting means cooperating with the compensating means, to effect said twist of the wire end portions tightly against said assembly of articles.

35. In apparatus for bundling elongated articles with wire, in combination, wire-carrying means movable about an assembly of articles, to form a loop of wire around the assembly, means disposed between said carrying means and the assembly, for twisting portions of the ends of the loop together on both sides of said twisting means, means for severing the twisted wires at the ends of both twists remote from the loop, whereby the twisted loop is freed and a slug of twisted wire remains in the twisting means, and means for ejecting said slug from the twisting means.

36. In apparatus for bundling elongated articles with wire, in combination, a wire-carrying ring disposed to surround an assembly of articles and rotatable to draw the end of a wire around said assembly, to form a surrounding wire loop, means for arresting said ring at a predetermined terminal position, a twisting device disposed within the ring and adapted to engage both the end portion and the standing portion of the wire loop,

37

means controlled upon termination of rotation of the ring for operating said twisting device to twist the wire portions together on both sides of said device, means for severing the twisted wires at the ends of both twists which are remote from the loop, whereby the twisted loop is freed and a slug of twisted wire remains in the twisting device, a device for ejecting said slug from the twisting device, and means controlled by the ring and responsive to a subsequent rotation thereof, for operating said ejecting device.

37. The apparatus described in claim 34 in which the twisting device comprises a rotatable member having a radial slot receiving both said portions of wire, and said ejecting device comprising an arm pivotally mounted on the ring and adapted to swing through said slot, said operating means for the ejecting device comprising an actuating element associated with said arm and a stationary cam element, said ring being adapted to move said actuating element past said cam element for swinging the arm through the slot of the twisting device.

38. In apparatus for bundling elongated articles with wire, in combination, a plurality of spaced devices for wrapping wire about an assembly of articles at correspondingly spaced localities along said assembly, movable means for advancing such assembly endwise into position adjacent said devices for operation thereof, at said localities, means shiftable relative to said movable means, for separating said assembly therefrom, to support the assembly during oper-

38

ation of the wrapping devices, and means adapted to be controlled by the assembly of devices and responsive to arrival of same in said position for wrapping operation, for initiating operation of the separating means, the aforesaid movable means comprising a plurality of rollers respectively associated with the devices and having actuating means therefor, and the aforesaid separating means comprising a plurality of vertically shiftable plates respectively associated with the devices and each having an upwardly opening notch to receive the assembly of articles, and means for shifting said plates upwardly, said means responsive to the position of the assembly comprising control means for the plate shifting means and the wrapping devices, for simultaneously operating the separating means and initiating operation of the wrapping devices.
